UNITED STATES PATENT OFFICE.

GUSTAVUS MICHAELIS, OF ALBANY, NEW YORK.

PROCESS FOR PURIFYING CHLOROFORM.

1,203,032.

Specification of Letters Patent. Patented Oct. 31, 1916.

No Drawing.

Application filed July 12, 1916. Serial No. 108,877.

To all whom it may concern:

Be it known that I, GUSTAVUS MICHAELIS, a citizen of the United States of America, residing at the city of Albany, in the county of Albany and State of New York, have invented a certain new and useful Process for Purifying Chloroform, of which the following is a specification.

This invention relates broadly to the manufacture of purified chloroform from ordinary or impure chloroform obtained by the usual well-known methods.

Chloroform has been known for nearly one hundred years and it has been, and is at present, produced from a great many different bodies, of which the most important are alcohol, chloral, acetone, carbon-tetra-chlorid, and aldehyde; but no matter from what source or starting material it may have been obtained, it always contains by-products or impurities so called, which should be eliminated before it can be used for medicinal or anesthetic purposes. The removal or destruction of these impurities has always been a difficult problem and it has heretofore only been possible to effect their partial elimination. The principal agent for the removal of these impurities has been, and is, concentrated sulfuric acid of 66° B. strength; for instance, distillation with or over sulfuric acid was resorted to, but it was found that this method yielded a chloroform which left, upon evaporation on blotting paper or otherwise, a disagreeable residual odor, which made it unfit for medicinal and especially anesthetic purposes. Then shaking of impure chloroform with concentrated sulfuric acid of 66° B. at ordinary temperatures was recommended and it was made the official method published in the pharmacopœias of the United States and other countries. By this method, however, only those impurities are eliminated which can be destroyed by the action of cold sulfuric acid, leaving those impurities intact which are only acted upon or destroyed by hot sulfuric acid. The failure of either of these processes to give satisfactory results is due to the fact that the action of sulfuric acid upon the impurities contained in the impure chloroform has heretofore not been understood. Sulfuric acid exerts a powerful action upon many organic bodies, and while this action is strong at ordinary temperatures, it is greatly intensified when it is allowed to act upon these bodies at a higher

temperature, while in some cases this action only commences at such higher temperatures, the sulfuric acid being without action at ordinary temperatures.

In the manufacture of impure or crude chloroform, there originate many by-products with the chloroform, all of which, with the exception of chloroform itself, are acted upon by sulfuric acid. But I have found that there is a difference in its action. There are some impurities which are acted upon by sulfuric acid in the cold or at ordinary temperatures, while others are only acted upon at higher temperatures or around the temperature of chloroform heated to or near its boiling point.

In order to obtain chloroform which is of ideal purity, it is necessary and essential that the sulfuric acid, which is used when chloroform is treated with it in the cold, be removed as it contains all the impurities which can be acted upon, or they are destroyed, to a degree at least, by this cold sulfuric acid. If the used sulfuric acid is not removed and the chloroform is heated with the same sulfuric acid, this latter exercises a further decomposing influence upon the impurities which have been partly destroyed by the cold sulfuric acid, and it leaves the chloroform with an offensive odor. This point, that is, the careful removal of the sulfuric acid which contains the impurities destroyable by it at ordinary temperatures, is the pivotal point upon which turns the eventual purity of the chloroform after having been subjected to the further action of sulfuric acid at the boiling temperature of chloroform, the reason being that the hot sulfuric acid exercises a further decomposing action upon the by-products present in the impure chloroform if not removed after the action of cold sulfuric acid. This is shown:

First: When one hundred cubic centimeters of purified chloroform, obtained by this cold sulfuric acid method, are evaporated on a water bath to ten cubic centimeters, the remaining ten cubic centimeters leave a disagreeable residual when evaporated upon blotting paper. This is the so-called odor test.

Second: When fifteen cubic centimeters of colorless, chemically pure sulfuric acid are shaken with twenty cubic centimeters of this purified chloroform and eight drops of a forty per cent. solution of formaldehyde in

a glass stoppered cylinder, the sulfuric acid is readily discolored, showing the presence of impurities which render it unfit for anesthetic purposes. This is the so-called formaldehyde sulfuric acid test.

I have invented a process of treatment, however, by the practice of which all of the impurities may be removed. My process is as follows: One hundred parts of chloroform are first shaken in a suitably constructed apparatus with thirty-three parts of cold, colorless, concentrated sulfuric acid of 66° Be. until a sample, after full separation from the now highly-discolored sulfuric acid, no longer imparts a color to colorless, chemically pure sulfuric acid when the same is vigorously shaken with it for at least five minutes, the proportion being about five cubic centimeters of sulfuric acid and fifty cubic centimeters of chloroform, showing the removal of all impurities which can be eliminated by the action of cold sulfuric acid of 66° Be. strength. All of the highly-colored acid is now carefully removed from the chloroform and a new quantity of thirty-three per cent. of colorless sulfuric acid of 66° Be. is added to the chloroform while it still remains in the apparatus in which it has been previously shaken with the acid. The mixture is then shaken while heat is applied to same until its temperature reaches or approaches the boiling point of chloroform, say 55° to 60° C. It is kept at this temperature for three to four hours, the volatilized chloroform being condensed and returned to the apparatus either by means of a reflex cooler or by any other suitably constructed contrivance. The heating is then discontinued, but the agitation is kept up for a further four to six hours until the mixture has cooled, when it is allowed to settle. The chloroform is then removed from the sulfuric acid and transferred to a tank in which it is repeatedly washed with water and a suitable alkali until it shows neutral with litmus paper to prove that the last traces of sulfuric acid have been removed. This done, the chloroform is transferred to a still and distilled over a dehydrating agent, such as calcium chlorid or potassium carbonate, or any other suitable agent. After the first ten parts of chloroform have distilled over, the receiver is changed and the next sixty to seventy parts of distillate are put away as perfectly pure chloroform, while what is left in the still is, after cooling, returned to the shaker, together with the first ten parts of distillate obtained, to be subjected again to the purifying treatment with an additional quantity of sulfuric acid of 66° B. and a new lot of impure chloroform. In other words, the results of the operation are from sixty to seventy parts of absolutely pure chloroform. It is well known that

chemically pure chloroform does not keep unless from six-tenths to one per centum of absolute alcohol are added, and this must therefore be done at once to secure its stability. Chloroform which has been treated as described is free from all impurities and will answer the most rigid tests which can be applied, to wit: First: If one hundred cubic centimeters of chloroform purified as described are evaporated on a water bath to ten cubic centimeters, the remaining ten cubic centimeters will leave "no residual odor" when volatilized upon blotting paper,—the so-called odor test. Second: If fifteen cubic centimeters of colorless, chemically pure sulfuric acid are shaken with twenty cubic centimeters of chloroform, purified as described, and eight drops of a forty per cent. solution of formaldehyde in a glass stoppered cylinder, the sulfuric acid will not be discolored within one hour and will show only a faint discoloration after twenty-four hours, showing absence of all organic impurities,—the so-called formaldehyde sulfuric test. Third: If five cubic centimeters of colorless, chemically pure sulfuric acid are shaken for five minutes with fifty cubic centimeters of thus purified chloroform in a glass stoppered cylinder, neither the chloroform nor the sulfuric acid will show a discoloration after from twenty-four to forty-eight hours.

An example of carrying out the described process is the following: 1710 pounds of impure chloroform and 570 pounds of sulfuric acid of 66° Be. are placed in a suitable apparatus and are agitated for about four hours. The mixture is then allowed to settle for one and one-half hours, when the now highly-discolored acid is drawn off, taking care to remove it all as completely as possible. The apparatus still containing the chloroform is charged anew with 570 pounds of sulfuric acid of 66° Be. and a second agitation is started, but the mixture is now heated to a temperature of from between 55° to 60° C. This shaking and heating is kept up for about four hours when the heat is withdrawn, and after further agitation for about six hours the agitation is stopped and the mixture is allowed to cool and to separate. After this is done the supernatant chloroform is drawn off and transferred to a tank where it is repeatedly washed with water containing enough of an alkali to free it from the last traces of sulfuric acid, the accomplishment of which is ascertained by means of litmus. The neutral or slightly alkaline chloroform is then placed in a distillatory apparatus and distilled over either dry calcium chlorid or dry potassium carbonate, the object being the removal of the last traces of water. The result obtained is: 100 lbs. of first portion rejected as having a very slight odor and showing slight discoloration with

the formaldehyde sulfuric acid test. 1400 pounds of main portion, standing both the odor and formaldehyde-sulfuric acid tests. 200 pounds (about) left in still, to be re-
 5 worked together with the first hundred pounds of slightly impure chloroform re-
 jected as unfit for use at the beginning of the distillation. The 1400 pounds of absolutely pure chloroform obtained are imme-
 10 diately mixed with six-tenths to one per centum of absolute alcohol to insure its keep-
 ing qualities.

What I claim as my invention and desire to secure by Letters Patent is:

15 1. The process of purifying chloroform, comprising shaking together one hundred parts of chloroform and thirty-three parts of sulfuric acid of 66° B. placed in a suitable receptacle, until a sample, after full
 20 separation from the now highly-discolored sulfuric acid, no longer imparts a color to colorless, chemically pure sulfuric acid when the same is vigorously shaken with it for at least five minutes, then removing the highly-
 25 colored acid from the chloroform and adding a new quantity of thirty-three parts of colorless sulfuric acid of 66° B. to the chloroform, shaking the mixture and applying heat thereto until its temperature reaches
 30 or approaches the boiling point of chloroform, condensing the volatilized chloroform and returning it to the mixture, then discontinuing the heat, but continuing the agitation for a time and allowing the mixture
 35 to settle and to cool, withdrawing the chloroform from the sulfuric acid, treating it

with a suitable alkali until the last traces of sulfuric acid have been removed, then dehydrating the same and placing it in a still, distilling the chloroform and after collecting the perfectly pure chloroform adding to it for preserving it, absolute alcohol.

2. The process of purifying chloroform, comprising placing in a suitable receptacle one hundred parts of chloroform with thirty-
 45 three parts of colorless, concentrated sulfuric acid and agitating the mixture, removing from the chloroform the acid which has become highly discolored after agitation for a sufficient length of time, then adding 50 a new quantity of thirty-three parts of colorless, concentrated sulfuric acid, agitating the mixture and applying heat thereto until the mixture reaches substantially the boiling point of chloroform, condensing the vapor 55 and returning it to the mixture in liquid form, continuing the agitation and recondensation of the vapors, then, after cooling, removing, washing and dehydration of the chloroform, subjecting the same to distillation, rejecting the first ten parts of distillate as slightly impure chloroform and collecting the next sixty to seventy parts as pure chloroform, adding to same from six-tenths to one per cent. of alcohol for preservation.

In testimony whereof I have affixed my signature in presence of two witnesses.

GUSTAVUS MICHAELIS.
